ROTARY LIPSTICK HOLDER

Simon Morrison, New Brunswick, N. J.

Application November 26, 1940, Serial No. 367,157

9 Claims. (Cl. 206—56)

This invention relates to lipstick holders used for housing lipstick and rendering the same readily available for application to the lips. The invention is particularly applicable to rotary lipstick holders, i. e., holders of the type in which the lipstick is housed in a cylindrical container and is projected therefrom for use by rotation of an operating head relative to the exterior casing of the container proper.

"Lipsticks" are usually made of a soft colored composition used for coloring the lips. However, the identical holders are sometimes used for sticks of cocoa butter, styptic material, etc. It is convenient to still refer to the holders as "lipstick holders" when they are so used; and that term as used herein includes such uses.

Rotary lipstick holders are conventionally provided with a protective dust cap that is applied to the holder when the same is not being used for applying lipstick. This protective cap is of inverted cup-shape and covers the mouth of the holder from which the lipstick is projected for use. When the cap is in use it is held in place on the holder by the depending cylindrical skirt of the cap which frictionally embraces the outer casing of the holder proper. When such a lipstick holder is being carried in a pocketbook or handbag, it often happens that shifting and turning of the contents of the bag causes relative rotation between the operating head and the dust cap, which relative rotation is transmitted to the embraced casing of the holder proper, thereby advancing the lipstick. This brings the lipstick in engagement with the dust cap, thereby deforming the lipstick, smearing it around, and in some instances more or less gumming up or jamming the operating mechanism. The same sort of difficulty, in even more marked degree, is often caused by lipstick owners twirling them idly in their hands while sitting and talking in restaurants, etc. Often the owner will idly turn the operating head while the dust cap is in place, thereby quite forcibly jamming the lipstick against the dust cap and squeezing it into crevices of the mechanism.

The principal object of the present invention is to provide a rotary lipstick holder which is protected against inadvertent or accidental advancing of the lipstick while the protective dust cap is in place.

A more specific object of the invention is to provide a rotary lipstick holder including a dust cap from which rotary movement cannot be transmitted to the operating casing of the holder proper.

A further object of the invention is to provide a lipstick holder having a dust cap detachably secured in protective or carrying position in an improved manner.

5 Fig. 1 of the drawings is an enlarged elevational view of a lipstick holder embodying the present invention.

Fig. 2 is a central vertical section of the holder shown in Fig. 1, on a still larger scale.

10 Fig. 3 is an isometric view of the operating head and operating fingers which are secured thereto.

Fig. 4 is an elevation of the operating casing shown in Fig. 2, this casing being the exterior casing of the holder proper.

15 Fig. 5 is a perspective view of the stick carrier shown in Fig. 2.

Fig. 6 is a horizontal section taken on line 6—6 of Fig. 2.

20 With the exception of the operating head, the various parts are preferably made of sheet metal (for example, brass); and as usual, the thickness of sheet metal is exaggerated in the drawing. The operating head may be made in a single piece on an automatic screw machine, brass being a suitable material. The exterior parts of the holder may be finished or decorated in any suitable and desired manner.

25 A cylindrical sheet metal shell or casing, designated as a whole by 10, has its upper portion necked in at 11 and further necked in at 11a. The upper end of this shell is formed into an inturned annular flange 12. On the outer wall of the cylinder 10 there are various indentations such as 13 which are all part of one or more series of indentations corresponding to a single or multiple thread respectively. These indentations are preferably of spherical form, i. e., the surface of each indentation corresponds in shape

30 to the curved surface of a segment of a sphere. Preferably these indentations are arranged in a plurality of vertical rows on the cylinder 10, but all of the indentations also lie on a helical path or paths on the cylinder 10. In the particular arrangement shown in the drawing there are two vertical rows of indentations 13 positioned diametrically opposite on the cylinder 10. There are also two helical paths corresponding to a double thread, i. e., there are two interspersed parallel

35 40 45 50 55 helical paths, alternate indentations lying on one path and the intermediate indentations lying on the other path. Since the shell is made of sheet metal, the indentations 13 are accompanied by corresponding spherical protuberances 14 on the interior of shell 10. Adjacent the bottom of the

cylinder 10 there may be provided one or more instruck spring tabs 15 (two shown) which may be utilized in assembling the lipstick holder.

The carrier, designated as a whole by 18, comprises a bearing skirt 19, a thimble portion 19a, a cup or socket 20, and an annular flange 21 which acts as a connecting means that unites the skirt and socket. Parts 19, 19a and 21 are formed in one piece. The cup or socket 20 is a separate piece, having a hole 20a in its bottom and being prick-punched connected as at 20b to thimble 19a. As usual, the cup 20 is adapted to receive and support a lipstick S. On the exterior of skirt 19 there is formed a male thread 22 of rounded cross section. In the particular form shown in the drawing this thread is a double thread, corresponding to the double thread arrangement of the protuberances 14. The annular flange 21 is pierced by two arcuate slots 24, 24, for a purpose that will be explained later.

The operating head 23 may be formed in one piece, and it has a cylindrical grip portion 23a, a superimposed portion 23b of smaller diameter and a top portion 23c of still smaller diameter. The grip portion 23a may be provided with grooves 25a which are ornamental and make this portion somewhat easier to grasp by the user. The portion 23b is grooved at 25b, leaving a projecting annular flange 26. The upper portion 23c is grooved at 25c, leaving an annular flange 27. Projecting upwardly from the top of the operating head is an integral boss 29 which is adapted to be cut or swaged so as to act as a rivet. Attached to the operating head 23 by the rivet formation 29 is an operating member designated as a whole by 30. Member 30 has a tubular bottom portion 31 that is provided with an end wall 32 which is non-circularly pierced at its center for fixed attachment to the operating head by the rivet member 29, as shown in Fig. 2. Projecting upwardly from the tubular portion 21 are two standards or fingers 34, 34, each of which is of arcuate cross section, since these standards are continuations of sectors of the tubular portion 31. When the member 30 is assembled on the head 23, as shown in Figs. 2 and 3, these two parts are so related that rotation of head 23 rotates member 30.

The carrier 18 is screwed into the cylindrical shell or casing 10 from the bottom, the tabs 15 being located on continuations of the helical paths established by protuberances 14. The standards 34, 34 are inserted from the bottom through the slots 24, 24 and the upper flange 27 of the head 23 is forcibly telescoped into the bottom of the cylinder 10. This causes the spring tabs 15, 15 to snap into the annular groove 25c and thereby hold the parts together. In the alternative the cylindrical casing 10 can be initially formed without the tabs 15, 15, and after assembly with respect to the operating head, metal can be punched from the bottom of sleeve 10 as at 15, 15 to project into groove 25c and hold the parts together.

It will be noted from Fig. 2 that the standards or fingers 34, 34 make a bearing fit with the exterior surface of thimble 19a and also with the interior surface of the necked in portion 19a of tube 10. The cylindrical surface of the skirt 19 also makes a suitable bearing fit on the interior cylindrical surface of the casing 10. Thus, the various parts mutually engage and support one another for easy coaction and movement.

With the tabs 15, 15 located in the annular groove 25c, the head may be rotated with respect

to the casing 10. When so rotated, the standards 34, 34 impart rotary motion to the carrier 18. Rotation of the carrier 18 causes the helically disposed protuberances 14 to exert a longitudinal force on the thread 22, with the result that the carrier is moved longitudinally in the casing 10. Thus, the lipstick S is readily projected for use and then retracted again for carriage.

The holder proper is provided with a removable dust cap 35 which telescopes over the top of the holder and makes a loose or non-friction fit with the exterior of casing 10. This cap extends the full length of the casing and its lower end is enlarged at 36 to telescope over the flange 26, as shown in Fig. 2. Struck inwardly from the lower portion 36 of the dust cap are small portions 37, 37 forming internal protuberances that snap into the groove 25b when the cap is in place. Considering together the enlarged portion 36 of the dust cap and the struck-in portions 37, 37, the dust cap makes a swivel engagement with the operating head when the cap is in place. Due to the loose fit between the body of the dust cap 35 and the exterior of casing 10, the dust cap also makes a swivel fit with casing 10. It will be seen, therefore, that if the head 23 be rotated accidentally or otherwise while the dust cap is in place the casing 10 will likewise freely rotate within the dust cap 35 and therefore no relative rotation can occur between the head 23 and the casing 10. Thus the lipstick cannot be accidentally or inadvertently advanced while the dust cap 35 is in place, and the owner can use the device as a toy and twirl the operating head idly if she chooses.

To use the lipstick the dust cap 35 is simply pulled off of the holder, whereupon the holder can

be operated in the usual manner to advance and

retract the lipstick.

In compliance with the patent statutes, I have shown the best form in which I have contemplated applying my invention. It will be understood, however, that the disclosure is illustrative of the invention, not limited.

What I claim is:

1. In a rotary lipstick holder having a casing, an operating head rotatable relative to the casing to advance and retract a lipstick, and a telescopic closure cap for the casing; the improvement which comprises: the closure cap loosely fitting the casing and being swivelly connected to the operating head, whereby the holder is protected against accidental relative rotation between the operating head and said casing.

2. In a rotary lipstick holder having a casing, an operating head rotatable relative to the casing to advance and retract a lipstick, and a telescopic closure cap for the casing; the improvement which comprises: the closure cap loosely fitting the casing and being swivelly connected to the operating head by a quick-detachable connection, whereby the holder is protected against accidental relative rotation between the operating head and said casing.

3. In a rotary lipstick holder having a casing, an operating head rotatable relative to the casing to advance and retract a lipstick, and a telescopic closure cap for the casing; the improvement which comprises: the closure cap loosely fitting the casing and covering the casing throughout substantially its entire length, and there being means to swivelly hold the closure cap in protective position; whereby the holder is protected against accidental relative rotation between the operating head and said casing.

4. In a rotary lipstick holder having a casing,

an operating head rotatable relative to the casing to advance and retract a lipstick, and a telescopic closure cap for the casing; the improvement which comprises: the closure cap loosely fitting the casing and covering the casing throughout substantially its entire length, and there being quick-detachable swivel means to hold the closure cap in protective position; whereby the holder is protected against accidental relative rotation between the operating head and said casing.

5. In a rotary lipstick holder having a casing, an operating head rotatable relative to the casing to advance and retract a lipstick, and a telescopic closure cap for the casing; the improvement which comprises: the operating head being provided with an annular groove, and the closure cap being provided with retaining means engaging said groove and swivelly attaching the closure cap to the operating head.

6. In a rotary lipstick holder having a casing, an enlarged operating head rotatable relative to the casing to advance and retract a lipstick, and a telescopic closure cap for the casing; the improvement which comprises: the closure cap inclosing the casing throughout its entire length and being provided with an enlarged end portion telescoping over the upper part of the operating head, and said head and said end portion being provided with interfitting relatively rotatable formations securing the closure cap in place and swivelly connecting the closure cap to the operating head.

7. In a rotary lipstick holder having a casing, an enlarged operating head rotatable relative to the casing to advance and retract a lipstick, and

5 a telescopic closure cap for the casing; the improvement which comprises: the closure cap inclosing loosely fitting the casing throughout its entire length and being provided with an enlarged end portion telescoping over the upper part of the operating head, and said head and said end portion being provided with interfitting formations swivelly securing the closure cap in place.

10 8. In a rotary lipstick holder having a casing, an enlarged operating head rotatable relative to the casing to advance and retract a lipstick, and a telescopic closure cap for the casing; the improvement which comprises: the closure cap 15 loosely fitting the casing throughout its entire length and being provided with an enlarged end portion telescoping over the upper part of the operating head, said head being provided with an annular groove and said end portion being provided with inwardly projecting means which snap into said groove and swivelly secure the closure cap to said head.

20 9. In a rotary lipstick holder having a casing, an enlarged operating head rotatable relative to the casing to advance and retract a lipstick, and a telescopic closure cap for the casing, the improvement which comprises: the closure cap 25 inclosing the casing throughout its entire length and being provided with an enlarged end portion telescoping over the upper part of the operating head, said head being provided with an annular groove and said end portion being provided with inwardly projecting means which snap into said groove and secure the closure cap to said head.

SIMON MORRISON.
